TRUCK HAVING A CONVERTIBLE REAR SECTION

Stanley R. Putnam, County Road P.O. Box 82
East Woodstock, Conn. 06244

Filed Jan. 8, 1973, Ser. No. 321,729

Term of patent 14 years

Int. Cl. D12—08

U.S. Cl. D12—99

FIG. 1

FIG. 2

FIG. 3

FIG. 4

FIG. 5

FIG. 1 is a side elevational view of a truck having a convertible rear section showing my new design and in which the top, side and rear walls are removable to form a flat-bed construction;

FIG. 2 is a top plan view thereof;

FIG. 3 is a side elevational view opposite to that illustrated in FIG. 1;

FIG. 4 is a front elevational view thereof; and

FIG. 5 is a rear elevational view thereof.

I claim:

The ornamental design for a truck having a convertible rear section, as shown and described.
